ROOFING AND SIDING ELEMENT

Norman P. Harshberger, Pasadena, Calif., assignor to Bakelite Building Products Co. Inc., New York, N. Y., a corporation of Delaware

Application March 3, 1930. Serial No. 432,947

2 Claims. (Cl. 108—7)

This invention relates to improvements in roofing and siding elements.

It is one of the objects of this invention to provide an improved roofing and siding element having water-proofing and bituminous material applied to both sides thereof, in which said sides are colored differently so that they may be used interchangeably to produce various effects upon the roof.

One of the novel features of the invention resides in the manner of forming indented definition lines on the elements to create the effect of individual shingle thereon. If the indented definition lines on one side were directly in line with those on the other side, the material would be considerably weakened along the edges of the figures and its capacity to withstand weather and breakage would be greatly diminished.

It is therefore an object of this invention to provide a single element in which the definition lines on one side are offset with relation to those on the other side, so that the material will not be unduly weakened by reason of said definition lines.

It is a further object of this invention to provide an improved roofing and siding element which is simple in construction, attractive in appearance, and well adapted for the purpose described.

With the above and other objects in view, the invention consists of the improved roofing and siding element, and all its parts and combinations, as set forth in the claims, and all equivalents thereof.

In the accompanying drawing, in which the same reference numerals designate the same parts in all of the views:

Fig. 1 is a plan view of a roofing and siding element; and

Fig. 2 is a sectional view taken on line 2—2 of Fig. 1.

Referring to the drawing, the numeral 8 designates the base of the roofing and siding material, which is preferably felt. Each side of the base is coated with a layer of asphalt 9 or other waterproofing material. Sprinkled over and partially embedded in the asphalt, on each side, is a layer of mineral material 10, such as granulated slate. The slate and asphalt on one side

may be of one color or a combination of colors, and the slate and asphalt on the other side may be of a different color or different combination of colors. The roofing and siding elements may be of any desired shape, the drawing illustrating an

element having semi-hexagonal tabs projecting therefrom.

In order to complete the hexagonal figures, indented definition lines 11 are formed on the body of the elements on one side. The said lines are preferably produced by applying heat and pressure to depress the surface, or by applying pressure alone while the surface coating is in a semi-liquid state. Similar lines 12 are formed on the other side of the element, said lines, however, being offset with relation to the lines 11, as clearly shown in Fig. 2. If the lines 11 were directly above the line 12, there would be only a very thin portion of material between, and the roofing and siding elements would be dangerously weak, also the said lines. By having the lines offset, however, this objectionable feature is overcome.

Inasmuch as each element has two usable sides, carrying different color effects, the side of each element may be used which best fits into the color scheme which it is desired to carry out on the roof. Thus, the roofing contractor is able to carry out a wide range of color effects with a much smaller stock of shingle elements than if each element had only one finished side.

Although only one form of roofing and siding element has been shown and described, it is to be understood that the invention comprehends all changes and modifications as may come within the scope of the claims.

What I claim is:

1. A roofing and siding element comprising a fibrous base having a weather protecting coating on both sides thereof, one of said sides having definition lines formed thereon by indentation of the surface coating to a depth not greater than the depth of the coating to leave the base unaffected, and the other of said sides having similarly formed definition lines of like depth, the definition lines on the two sides forming figures of substantially similar shape and of substantially identical position on the two sides, the definition lines on one side being offset with relation to the definition lines on the other side to prevent weakening of the material, and the figure on one side being smaller in size than in the figure below on the other side by the amount of said offset.

2. A roofing and siding element comprising a fibrous base having a weather protecting coating of substantially the same thickness as used in standard practice on both sides thereof, one of said sides having definition lines formed thereon by indentation of the surface coating to a depth

not greater than the depth of the coating to leave the base unaffected, and the other of said sides having similarly formed definition lines of like depth, the definition lines on the two sides forming figures of substantially similar shape and of substantially identical position on the two sides, the definition lines on one side being offset with

relation to the definition lines on the other side to prevent weakening of the material, and the figure on one side being smaller in size than the figure below on the other side by the amount of said offset.
